Atty.

UNITED STATES PATENT OFFICE.

STANLY ZAVE, OF CHICAGO, ILLINOIS.

STOVEPIPE-CLEANER.

1,362,660.

Specification of Letters Patent. Patented Dec. 21, 1920.

Application filed December 1, 1919. Serial No. 341,821.

To all whom it may concern:

Be it known that I, STANLY ZAVE, a citizen of Lithuania, and a resident of Chicago, in the county of Cook and State of Illinois, have invented certain new and useful Improvements in Stovepipe-Cleaners, of which the following, when taken in connection with the drawing accompanying and forming a part hereof, is a specification.

10 This invention relates to a device by means of which the horizontal portion of a stove pipe may be cleaned.

Among the objects of the invention are to obtain an inexpensive means of keeping the 15 horizontal portion of a stove pipe, in the home or factory, cleaned of soot and ashes. A further object is to obtain a device which will at all times be in position and condition for use. A further object is to obtain a device of the kind named which when not in use, is not particularly noticeable; a device which is easily operated, not liable to break or get out of order, and comprising few parts.

25 In the drawing referred to Figure 1 is a vertical section of a short section of horizontal stove pipe, showing a cleaner and well therefor; and also showing a portion of a vertical section, partly in section.

30 Fig. 2 is a bottom plan view, looking upward, of the horizontal section of said pipe; and

Fig. 3 is a sectional view, on line 3—3 of Fig. 1, viewed in the direction indicated by 35 the arrows.

A reference character applied to designate a given part indicates said part throughout the several figures of the drawing, wherever the same appears.

40 A represents a section of a wall, provided with stove pipe aperture *a*. B represents a horizontal section of a stove pipe; and may be of any length, it being understood that the drawing is not made to a scale. *b* represents a vertical section of a stove pipe.

45 C represents an elbow to the stove pipe illustrated. Horizontal section B, elbow C and the upper part of section *b*, are shown in longitudinal section in Fig. 1. D represents a depending pipe communicable with horizontal section B, and is of substantially the same diameter as said section. *d* represents the curved under side of the joining of pipe D and section B. Ee, (Figs. 1 and 3) represents a slide positioned in the horizontal section B, and adapted to be moved from the

position thereof which is illustrated by full lines in Fig. 1, to the position which is indicated by broken lines in said figure, to close communication of said pipe D with said section, when the brush, hereinafter described, is not contained therein, and to partially close said communication when said brush is contained in said pipe or well. Said slide Ee is manually operable by handle F, and to permit the movement of said slide and handle the pipe B is provided with slot G in which the center rod *f* of said handle F is slidably movable. When slide Ee is in the position indicated by broken lines in Fig. 1, part *e* of said slide covers slot G. H represents a cap which is arranged to close the lower end of pipe D. I represents a cylindrical brush having the central portion or body part the ends *h* hereof are designated by characters J, and J¹. To end J of said brush I attach cord K which is coiled in cap H when said device is not in use; and to the end J¹ I attach arm K¹. *k* represents a cord, one end whereof is attached to arm K¹ and the other end to handle *k*¹. L represents a plate which is provided with aperture *l* registering with a corresponding aperture in vertical section *b*, through which the cord, (or chain) *k* extends, from the inside of pipe *b* to the outside thereof.

When the device is to be used for removing material, as soot and ashes, lodged on slide Ee and in the horizontal section B, cap H is removed and said slide Ee is moved into the position illustrated by full lines in Fig. 1, and by means of handle *k*¹ and cord *k* the brush I is drawn from pipe D into and along the horizontal section B, moving over the slide Ee and through said section.

When said brush I has been drawn the entire length of horizontal section B, thereby brushing soot and ashes contained in said section into the vertical section *b* of the stove pipe, said brush is returned to its initial position in pipe D by means of the cord K.

The above operation is repeated until said horizontal section B is cleaned, and thereupon cord K is coiled in cap H, and said cap replaced on pipe D, to close the lower end thereof. Slide Ee is then moved, by means of handle F to the position indicated by broken lines in Fig. 1, to prevent the accumulation of soot and ashes in said pipe D.

I claim:

In combination, a cylindrical stove pipe provided with a slot, a cylindrical well com-

municating with said pipe, of substantially the same cross section and having an opening in the bottom thereof, a curved member joining one side of said well and the under 5 side of said pipe and adjacent to said slot, a brush adapted to contact with the walls of said pipe and well, a member in said pipe arranged to cover said slot and adapted to be moved to obstruct communication between 10 said well and pipe when said brush is re-

moved from said well, a curved arm on said brush, a flexible connection attached to said arm and an additional flexible connection attached to said brush on the end opposite said arm, adapted to pass through the bottom 15 opening in said well.

STANLY ZAVE.

In the presence of—
KASIMIR P. GUGIO,
CHARLES TURNER BROWN.
